UNITED STATES PATENT OFFICE.

CHARLES J. WILLIAMS, JR., OF JACKSONVILLE, FLORIDA, ASSIGNOR TO L. MOORE DRY KILN CO., OF JACKSONVILLE, FLORIDA, A CORPORATION OF FLORIDA.

BASE-PLATE.

1,333,523.

Specification of Letters Patent.

Patented Mar. 9, 1920.

Application filed February 19, 1916. Serial No. 79,402.

To all whom it may concern:

Be it known that I, CHARLES J. WILLIAMS, Jr., a citizen of the United States, residing at Jacksonville, in the county of Duval and State of Florida, have invented certain new and useful Improvements in Base-Plates, of which the following is a specification.

My invention relates to an improvement in base-plates, the object being to provide a solid support for vertical posts or columns, and more particularly those that are commonly used in the track construction for dry-kilns, the object being to provide means to insure the lower surface being thoroughly surrounded by the soft concrete base, and permanently fastened therein.

In the accompanying drawings:

Figure 1 is a top view;

Fig. 2 is a bottom view; and

Fig. 3 is a section.

A, is the base casting, preferably although not necessarily round, with a central screw-threaded orifice 1 into which the lower threaded end of the column or post 2 is screwed. On the lower side, there are the inner and outer ribs 3 and 4, the former around the central orifice, and the latter at the outer edge, and the radial connecting ribs 5, 5, extending from the inner to the outer circular ribs.

At points say midway between ribs in the several spaces 6, surrounded by the ribs, the buttons or projections 7, 7, are cast integral, their lower edges being preferably flush with the lower surface of the several ribs, and they tapering so that their lower ends are larger than their upper ends where they join the metal of the base. The purpose of this construction is obvious, namely that it provides a fastening means which is embedded in the soft concrete and held fast by the latter as the concrete which has filled the open spaces 6, 6 between the ribs hardens.

So, although the length of the ribs and buttons or projections is comparatively short, they nevertheless constitute a firm and

substantial holding means or anchorage in the cement, after it sets and hardens, making it impossible to overturn the base from any amount of strain and weight, (which is, of course, great) to which a structure of this type is necessarily subjected.

In addition to the ribs and buttons or projections, it is customary also to secure the base to anchors 9 placed in the concrete a suitable distance below the base-plates by means of the bolts, 10, 10, inserted through the holes 11, 11, provided for that purpose in the base-plate, nuts 12, 12, being screwed thereon to hold the base-plate in place.

In this way, a solid foundation is provided; and a base when formed in this way is easily, quickly and securely set in the soft concrete which fills in around the buttons or projections and holds the entire base secure with uniformity at substantially equidistant points in its surface.

I claim:

The combination with a concrete foundation having fastening devices embedded therein, of a base plate adapted to be applied to the foundation while the outer surface of the latter is still in a plastic state, said base having an internally threaded central orifice to receive the threaded lower end of a column or post, and also provided with holes to receive the upper protruding ends of the fastening device extending from the foundation, the lower surface of the plate having integral concentric and radial ribs and buttons at intervals in the spaces between said ribs, the outer surfaces of which ribs and buttons are in approximately the same plane, which plane is beneath the plane of the bottom surface of the plate, whereby space is left for the plastic concrete between the ribs and around the buttons, whereby the base is secured by both the concrete and the fastening devices.

In testimony whereof I affix my signature.

CHARLES J. WILLIAMS, JR.
